(57) **CLAIM**

I claim the ornamental design for the steering wheel book holder, as shown and described.

DESCRIPTION

FIG. 1 is a front view of the steering wheel book holder.

FIG. 2 is a rear view of the claimed design.

FIG. 3 is a side view of the claimed design.

FIG. 4 is a top view of the claimed design.

FIG. 5 is a bottom view of the claimed design.

FIG. 6 is an isometric view of the claimed design with broken lines that represent the item in use on a steering wheel; and, FIG. 7 is an isometric view of the claimed design with alternate broken lines that represent the item in use on a steering wheel.

The broken lines in the drawings form no part of the claim.
